UNITED STATES PATENT OFFICE

JOHN I. BELLAMY, OF BROOKFIELD, ILLINOIS, ASSIGNOR TO RESERVE HOLDING COMPANY, OF KANSAS CITY, MISSOURI, A CORPORATION OF DELAWARE

TELEPHONE SYSTEM

Application filed May 25, 1928. Serial No. 280,427.

The present invention relates to telephone system but is concerned more particularly with improvements in sending devices used therein; and the object, generally stated, is the production of new and improved arrangements for securing a more uniform operation of the apparatus governed by sending equipment. The invention has been applied to register senders for use in multi-office automatic telephone systems, which register senders have come to be known as directors.

It is well known that automatic switching apparatus used in automatic telephone systems operates best when the impulsing circuit through which the impulses are transmitted to the switching apparatus varies in resistance through only relatively narrow limits, and that if the resistance varies through limits that are too great, the automatic switching apparatus often fails to respond properly. The greatest difficulty is experienced in multi-office systems wherein trunk lines varying widely in resistance are encountered. It has been found in practice that if arrangements can be devised for maintaining the resistance of the impulsing circuit practically constant, a great saving can be effected in the time and expense required to maintain the rigid adjustment which is necessary in case the impulsion resistance is not kept within rather close limits.

When register senders, less in number than the trunk lines with which they are associated, are employed in multi-office automatic telephone systems to receive digits transmitted from calling stations and to retransmit digits to the automatic switching apparatus, it becomes economical owing to the relatively small number of register senders to provide arrangements in the register senders to compensate for the varying resistances of the trunk lines over which impulses are transmitted.

It is an object of this invention to provide arrangements in a register sender automatically effective to add a local resistance to the impulse circuit of each low-resistance trunk line over which impulses are transmitted sufficient to raise the total resistance to a predetermined standard value.

It is a further object to provide arrangements such that the resistance of the impulse circuit is determined anew before each digit so that any alteration made necessary as a result of the switching operation performed in response to the preceding digit may be made.

General description

Referring now to the accompanying drawings comprising Figs. 1 and 2, they show by means of the usual circuit diagrams a sufficient amount of apparatus in a telephone system embodying the features of the invention to enable the invention to be understood.

Fig. 1 shows a telephone line leading from the automatic substation A to the exchange and terminating there in the individual line switch C, which has access to the first selector D by way of the trunk circuit TC which is individual to the selector D. The selector D has access to various local and inter-office trunks as indicated. The register sender selector DS is individual to the trunk circuit TC and has access to a plurality of register senders such as the one shown in Fig. 2 to which it has access over conductors 91-94.

Only a small portion of the register sender is shown in the drawings. This register sender may be the same as the shown in the Stehlík Patent 1,640,473, granted August 30, 1927, except for the addition of compensating relay 281-284 and the associated circuit connections as will be later explained.

It will be noted that Fig. 1 of the present disclosure and Fig. 1 of the above Stehlík patent are very similar to one another. The line switch C of the present disclosure may be the same as the line switch C of the patent, the same being true of the selector D. The trunk circuit TC in the present case has been changed to a holding circuit so as to avoid the necessity of outgoing repeaters, but the director selector DS, is the same as the director selector DS of the patent referred to.

In the present disclosure, wherever the parts are the same, the same reference numerals are applied as in the patent above referred to.

Detailed description

In order that the invention may be understood best, a detailed description of the operation of the apparatus shown will now be given. For this purpose it will be assumed that the subscriber at substation A desires that a connection be extended to another subscriber whose line terminates in the same office.

10

Local call

When the subscriber at substation A removes his receiver, the line switch C operates in the usual manner in search of an idle trunk. Assuming that the trunk extending through the trunk circuit TC to the selector D is the first one found to be idle, the line switch C seizes this trunk comprising conductors 25-27, whereupon line relay 31 operates over the calling line and closes a circuit for release relay 32. Release relay 32 operates and places ground on conductor 26 at a separate armature so as to maintain the established connection. At its two lower armatures, relay 32 causes the director selector DS to search for an idle register sender in the usual manner. When an idle sender is reached, the one shown in Fig. 2 for example, the hunting action of the switch DS ceases and relay 81 operates and completes the connection to the wipers 87-90, thereby extending a connection to the register sender of Fig. 2 over conductors 91-94.

When the wipers 87 and 88 are connected up, the usual line relay (not shown) of the selector D pulls up over conductor 91 and 92 of the register sender, preparing the selector D for operation. It may be pointed out that the circuit of the said line relay includes the normally-closed contacts controlled by the inner lower armature of pick-up relay 202, upper winding of relays 281-284, and armature 200 and its resting contact in parallel with sending contacts 233. Since the first digit to be transmitted is to the selector D over local cable connections of relatively low resistance, the current flow is sufficient to operate all of the marginal relays 281-284, whereupon each relay at its upper contacts inserts the associated resistance in the branch circuit and prepares a locking circuit for itself at its lower contacts.

The setting of the registering portion on the register sender now takes place responsive to the control exercised by means of the usual dial at the substation A through the medium of line relay 31 of the trunk circuit TC, which transmits the impulses from ground through the back contact of its inner lower armature over the associated conductor, and through contacts of relay 81 to impulse conductor 94 by way of wiper 90 of the switch DS.

After the setting of the registering appa-

ratus has proceeded to the proper point, the sending operation is started. The first step in the sending operation, as will be learned from the Stehlik patent above referred to, is the pulling up of the pick-up relay 202 so as to synchronize the sending operation with the operation of the controlling interruptor. When this relay pulls up it removes the shunt from the sending contacts 233 at armature 200. At its lower armature, relay 202 closes a locking circuit through contacts of stop relay 203 for the operated relays 281-284, while at its inner lower armature it alters the impulse circuit so as to include the resistances associated with relays 281-284 instead of the upper windings of these relays. Since all of the relays are operated due to the fact that a local switch is being controlled, each of the resistances is cut in the impulsing circuits as to bring the total resistance up to the required standard.

When the required number of impulses have been transmitted, stop relay 203 pulls up and shunts the impulse circuit at armature 211, at the same time bringing about the usual circuit changes including the circuit changes necessary to restore the sending switch to normal. These circuit changes are accomplished by contacts of relay 203 which are not essential to the present invention and are not shown in the present drawing. As a further result of the energization of stop relay 211, it opens the locking circuit of relays 281-284, whereupon these relays all fall back.

After the sending switch has been restored to normal, pick-up relay 202 falls back and stop relay 203 falls back a moment later and prepares the locking circuit on the compensating relays again.

Upon the falling back of pick-up relay 202, the relays 281-284, which are thereupon reinserted in the circuit at the contacts controlled by the inner lower armature of this relay, reset themselves for the second digit. Since, according to the previous assumption, the subscriber at substation A is calling a local number, the resistance of the impulse circuit is not materially greater than in the first place and all of the compensating relays pull up again, as they do following each digit.

It may be mentioned that the switch-through operation which takes place at the end of the transmission of the last digit is effected when a ground potential is applied over conductor 94, through wiper 90 of the switch DS, lower contacts of relay 81, lower armature, operated of relay 31, to switch-through relay 33, which locks itself to release trunk conductor 26 at its inner armature, at the same time completing a holding bridge across the conductors extending to the selector D through the right hand repeating coil windings and the lower contacts of relay 31. At its two inner armatures, relay 33 brings about the release of the selector DS.

by dropping back relay 81 and opening a further point in the test circuit of the switch. The falling back of relay 81 frees the register sender and removes the impulse bridge from across the talking conductors.

5 The release of the connection taking place responsive to the falling back of relays 31 and 32 when the calling subscriber hangs up his receiver.

10 *Call to office A*

Assume now that the subscriber at substation A is calling a subscriber at office A and that the operation has proceeded as hereinbefore described up to the sending out of the first digit. When the pick-up relay falls back following the sending out of this digit, the reoperation of relays 281—284 takes place on the basis of current flow over the inter-office trunk line from the calling office to office A. It may be assumed for purpose of illustration that this current flow is reduced to such an extent that relay 284, which is the fourth relay of the set, does not pull up. In this case, when the sending of the next digit starts upon the reoperation of pick-up relay 202, only relays 281—283 are operated and only three of the four compensating resistances are cut in.

30 It may be assumed for the purpose of illustration that the present call is for a sub-office of office A and that the so-called series holding circuit is employed in office A on the trunk lines leading to the sub-office, so that the impulse-circuit resistance is still further increased to that of a trunk line from office A to the sub-office. In this case, it may be arbitrarily assumed that the current flow is cut down to such an extent that only relays 281 and 282 operate when pick-up relay 202 again falls back.

40 *Call to office B*

Assuming now that a call is being extended 45 from the line of substation A in the manner hereinbefore described to a line terminating in office B, and assuming further that office B is a considerable distance away from the originating office so that the total resistance 50 in the impulsing circuit is already up to standard value, when pick-up relay 202 falls back after the first digit has been sent out, all of the compensating relays 281—284 remain non-operated and no additional resistance is cut in.

55 From the foregoing description it will be seen that the variation in resistance of the impulsing circuit is compensated for in any one of four steps and that when no compensation is needed, none is made, giving five different conditions. It will be understood that more or fewer compensating relays may be used, but the number shown is considered to be typical.

60 It will be understood of course that the

same arrangement for compensating for resistance in an impulse circuit may be employed when the so-called revertive control arrangement is used, such as for example, the revertive control arrangement of the Stearn Patent 1,505,171 granted August 19, 1924.

70 What is claimed is:

1. In a telephone system, an impulse circuit over which trains of impulses are transmitted incidental to the positioning of automatic switching apparatus, resistance compensating apparatus associated with said impulsing circuit, and testing means controlled over said impulse circuit for adjusting the compensating apparatus in accordance with the resistance of the circuit.

2. In a telephone system, an impulse circuit over which trains of impulses are transmitted incidental to the positioning of automatic switching apparatus, resistance compensating apparatus associated with said impulsing circuit, and testing means included in said apparatus and controlled over said impulse circuit between series of impulses.

3. In a telephone system wherein trains of impulses are transmitted over impulse circuits incidental to the positioning of automatic switching apparatus, a portion of an impulse circuit arranged to be supplemented by other portions of impulse circuits to form several complete impulse circuits during the setting up of a telephone connection, and automatic compensating means associated with the first impulse circuit portion and 100 automatically controlled thereover to compensate for resistance variations in the said supplementing portions.

4. In an impulse compensator for use in a telephone system wherein series of impulses are transmitted incidental to the positioning of automatic switching apparatus, resistance elements, testing means controlled over an impulse circuit for preparing to bring said elements into circuit, and a switching device 110 for excluding the testing means and for including resistance elements into circuit as predetermined by the position of the testing means after its operation over the impulse circuit.

5. In an impulse circuit for use in connection with the positioning of automatic switching apparatus, two branches for said circuit, one branch including marginal relay apparatus, the other branch including resistance apparatus controlled by the marginal relay apparatus.

6. In an impulse circuit for use in connection with the positioning of automatic switching apparatus, two branches for said circuit, one branch including marginal relay apparatus, the other branch including resistance apparatus controlled by the marginal relay apparatus, and means for completing the circuit through the relay branch between

impulse series and for completing it through the resistance branch during impulse series.

5 7. In a switching system, means including automatic switching apparatus for building up a connection by linking successive extensions to a line, a control circuit including said line and the extensions are they are linked thereto, means for controlling said apparatus over said circuit, and means controlled over 10 said circuit between successive extensions of said line for altering a characteristic of said line to compensate for the linked extensions.

15 8. In combination, automatic switching apparatus operable in stages, a control circuit and means for operating said apparatus in stages thereover, and means including testing apparatus applied to said control circuit between stages for maintaining a characteristic of said control circuit within predetermined limits.

20 In witness whereof, I hereunto subscribe my name this twenty-first day of May, A. D. 1928.

JOHN I. BELLAMY.
